UNITED STATES PATENT OFFICE.

HENRY L. REYNOLDS, OF SEATTLE, WASHINGTON, ASSIGNOR TO
BULLARD AUTOMATIC WRENCH COMPANY, OF LOS ANGELES,
CALIFORNIA, A CORPORATION OF CALIFORNIA.

WRENCH.

No. 824,081.

Specification of Letters Patent.

Patented June 19, 1906.

Application filed July 31, 1905. Serial No. 272,096.

To all whom it may concern:

Be it known that I, HENRY L. REYNOLDS, a citizen of the United States, and a resident of the city of Seattle, in the county of King and State of Washington, have invented certain new and useful Improvements in Wrenches, of which the following is a specification.

My invention relates to an improvement in wrenches and comprises the novel parts and combinations of parts which will be herein-after particularly pointed out in the claims.

The object of my invention is to improve and simplify such devices.

In the accompanying drawings I have shown my invention embodied in the form which is now preferred by me.

Figure 1 shows my improved wrench with the jaws in closed position. Fig. 2 shows the same wrench with the jaws in opened position.

My invention belongs to that class of wrenches which are capable of accommodating themselves to objects of a considerable range in size without the necessity of special adjustment of any parts—such, for instance, as turning a nut or shifting a pivot connection. It is further characterized by having a spring which acts to automatically close the jaws upon the object engaged.

I will now describe the device as shown in the drawings.

The jaw A has two principal parts—the shank A² and the hook A', which is designed to engage the pipe, nut, or other object to be turned. I have shown both jaws as designed especially to engage pipes and provided with teeth. It is, however, to be understood that they may be otherwise more especially adapted to engage nuts and be free of teeth, if desired. The complementary jaw B is mounted to slide upon the shank A² toward and from the hooked end A'. This jaw is preferably composed of two parts—the clip C, which embraces the shank A², and the filler-block F, the two parts being secured together, as by rivets b. The body of the shank is of substantially uniform cross-section, and the clip C and filler-block F are so spaced as to form an opening adapted to receive the shank with a free-sliding fit.

The handle H is preferably provided with two separated ears or web-like members H'

at its inner end, which are adapted to lie on opposite sides of the shank and filler-block 55 and be pivoted thereto, as by pivots h and h'. The preferred manner of constructing this handle is to make it out of a piece of plate metal bent into a channelled or U shape, thus forming the side webs H² and the connecting- 60 web H³.

The filler-block F is cut away on its edge next the shank to provide a recess for receiving the spring by which the jaws are normally caused to approach each other. This 65 leaves only a small lug f to engage this side of the shank. This is, however, amply strong to take the thrust, and being small in the extent of its contact permits the rocking of the jaw B as it is slid along the shank caused by 70

the link-like connection of the two jaws with the handle, whereby a snug fit may be obtained without binding. The opposite or pivot end of the shank is preferably extended farther than is necessary to secure strength 75 of metal about the pivot and is provided with a lug a, opposing in position to the lug f. Between these lugs and occupying the space and between the side faces of the clip and handle and between the shank and filler-block is 80 placed a helically-coiled wire spring G, which acts by compression to separate these lugs, and thereby force the two jaws together. To secure the end of the spring bearing upon lug a, I prefer to provide it with a pin g, which 85 enters the coil of the spring. A spring is easily inserted by throwing the jaws into the closed position, as shown in Fig. 1, pushing the spring into the socket, and compressing it until it may be allowed to expand over the 90 pin g. This spring is at all times inclosed and protected where it cannot be injured by throwing the wrench about.

What I claim, and desire to secure by Letters Patent, is—

1. A wrench comprising a jaw having a shank, a complementary jaw lying alongside the shank and having a clip embracing and adapted to slide upon said shank, a handle pivoted to said shank and complementary 100 jaw, and a spring lying alongside of and between said shank and the complementary jaw and engaging said parts to close the jaws.

2. A wrench comprising a jaw having a shank, a complementary jaw lying alongside 105 said jaw and having a clip embracing and

adapted to slide upon said shank, a handle having two separated webs adapted to lie on opposite sides of and pivotally connected with said shank and complementary jaw, and a 5 spring extending lengthwise the shank and between said shank and complementary jaw and between the two sides of said clip and handle-webs and acting to close said jaws.

3. A wrench comprising a jaw having a 10 shank extending at right angles thereto, a complementary jaw having a clip embracing and adapted to slide upon said shank, a handle comprising two separated webs joined by a connecting-web along one side edge and 15 having two transversely-separated pivots at its inner end connected respectively with said shank and complementary jaw, and a jaw-closing helical spring extending lengthwise the shank and lying between the sides of the 20 handle and of the clip and between said shank and complementary jaw and at opposite ends respectively engaging said shank and complementary jaw.

4. A wrench comprising a jaw having a 25 shank, a complementary jaw having a clip embracing and adapted to slide on said shank, said complementary jaw being cut away between the clips next the shank to form a spring-receiving chamber opening rearwardly, 30 a handle comprising two separated webs having two transversely-separated pivots at one end connected respectively with said shank

and complementary jaw, said shank having a spring-supporting projection between said handle-webs, and a coiled spring engaging 35 said projection by one end and with its other end in the chamber between the clip and engaging the complementary jaw.

5. A wrench comprising a jaw having a shank, a pivot near the outer end of the 40 shank and a side projection rearwardly of said pivot and toward the same side of the shank as the jaw-face, a complementary jaw comprising a block and a clip surrounding the shank and sliding thereon, said block having sliding engagement with the shank near the toothed edge and being cut away back thereof to form a spring-receiving pocket within the clip and between the shank and complementary jaw, a handle having two 45 transversely-placed pivots near one end engaging respectively with the shank and the complementary jaw, and a coiled spring engaging by one end with the side projection at the rear of the shank and with its other end 50 in the spring-receiving pocket of the complementary jaw.

In testimony whereof I have hereunto affixed my signature, this 22d day of July, 1905, in the presence of two witnesses.

HENRY L. REYNOLDS.
